UNITED STATES PATENT OFFICE.

CHARLES H. AYARS, OF SALEM, NEW JERSEY, ASSIGNOR TO AYARS MACHINE COMPANY, OF SALEM, NEW JERSEY.

CAN-FILLING MACHINE.

Application filed February 27, 1923. Serial No. 621,527.

To all whom it may concern:

Be it known that I, CHARLES H. AYARS, a citizen of the United States, residing at Salem, in the county of Salem and State of New Jersey, have invented certain new and useful Improvements in Can-Filling Machines, of which the following is a specification.

My invention relates to can filling machines and more particularly to means for agitating the materials and compressing them into the cans. Mechanism which is designed for use in canning granular materials may not function equally well with comparatively bulky material such as tomatoes or comparatively soft material such as string beans.

The objects of my invention are to provide improved means for agitating comparatively bulky or soft materials and compressing them into the measuring devices, and to provide such means which are readily adaptable for use with granular materials.

These objects, and other advantageous ends which will be described hereinafter, I attain in the following manner, reference being had to the accompanying drawings in which—

Figure 1 is a plan view of a canning machine embodying my invention,

Figure 2 a vertical section through the hopper and turret,

Figure 3 a plan view of the hopper plate,

Figure 4 an enlarged fragmentary section 35 on line 4—4 of Figure 1 showing the hopper and hopper plate at one limit of its oscillatory movement,

Figure 5 a like view showing the hopper and hopper plate at the limit of its swing in 40 the opposite direction,

Figure 6 a reversed plan view of a part of the hopper plate,

Figure 7 a section on line 7—7 of Figure 1, showing the hopper plate and shaker mechanism, the other parts being omitted, and

Figure 8 an end view of the shaker mechanism.

Referring to the drawings, 1 indicates the hopper and 2 the hopper plate which is provided with an upwardly extending flange 3 to the upper part of which the hopper is secured. The part of the flange below the hopper has a shouldered enlargement 4 in which is secured a compression member 5 of

rubber or other elastic material. The inner 55 wall of the compression member is curved at its upper and lower edges and slopes outwardly from the upper curved edge to the lower curved edge. The hopper plate preferably has a curved upwardly extending 60 groove 6, having a perforated top, extending from flange 3 to a point over the discharge port 7 of the turret 8, and communicating with the space within the compression member. This groove serves to convey granular 65 material, which might otherwise be crushed, to the discharge opening and also serves as an air vent. When the machine is in use for canning bulky or soft material the inner end of the groove may be closed by a detachable 70 plate 9.

Axial oscillation of the hopper is effective with granular material but not so effective with more bulky material and I have found that a swinging oscillation is equally or more 75 effective with both classes of material. I therefore provide means for imparting a swinging oscillation to the hopper plate and hopper. For this purpose I position one end of the hopper plate upon a boss 10 extending from the frame and yieldingly connect it therewith by a pivot pin 11 and a spring 12. The opposite end of the hopper plate carries a bracket 13 having a box like structure 14 at its outer end, the top of 85 which is provided with a longitudinal slot 14 and the bottom with a like slot indicated at 15. The interior of the box houses a block 16 which is slidable therein, and the box rests upon a wheel 17 adapted to be 90 rotated by any suitable mechanism. Wheel 17 carries an upwardly extending eccentric pin 18 which takes through slot 15, block 16 and slot 14 and is yieldingly held to the box by a spring 19. Rotation of wheel 17 causes 95 the hopper plate to oscillate with pivot pin 11 as the axis of oscillation.

I have illustrated the measuring wheel as consisting of telescoping sections 20 and 21, section 20 being supported by a bed plate 100 22, and the two sections being adapted to be rotated by means of a shaft 23 carrying a dog 24 disposed in an oblong opening 25 in a part 26 depending from section 20 of the measuring wheel. Section 20 of the measuring wheel has a threaded periphery 27 embraced by an inwardly threaded band 28 by rotation of which the telescoping sec-

tions may be adjusted to vary the capacity of the measuring receptacles.

The operation will be best understood by reference to Figures 4 and 5 of the drawings, it being understood that the hopper is filled and the shaker mechanism in operation and the hopper and compression member thereby caused to swing to and fro over the measuring receptacle which is being charged. Figure 4 shows the measuring receptacle partly filled and the hopper at the limit of its throw to the left and Figure 5 shows it at the limit of its throw to the right. As it moves from left to right the part of the sloping compression member at the left exerts a wedging pressure tending to press the fruit inwardly and downwardly into the measuring receptacle as shown in Figure 4. As the hopper is swung from right to left the part of the sloping compression member at the right tends to press the fruits inward and downward and the fruits are gently and snugly packed into the measuring receptacle.

25 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

30 35 Having thus described my invention, what I claim as new and desire to secure by Letters Patent is:—

1. In a can filling machine, the combination with traveling measuring receptacles of a plate carrying a hopper and having a pivot, adjacent one edge, connecting it with the frame, and means for swinging the plate to and fro, with the discharge opening of

the hopper over the measuring receptacles, with said pivot as an axis.

2. In a can filling machine, a plate carrying a hopper and a yielding compression member disposed under the throat of the hopper.

3. In a can filling machine, a plate carrying a hopper and a yielding compression member disposed under the throat of the hopper, the compression member having its interior wall sloping downwardly and outwardly.

4. In a can filling machine, a plate carrying a hopper and a yielding compression member disposed under the throat of the hopper, the compression member having its interior edges curved and its interior wall sloping downwardly and outwardly.

5. In a can filling machine, the combination of traveling measuring receptacles, a plate carrying a hopper and mounted to swing to and fro with the discharge opening of the hopper over the measuring receptacles, and a yielding compression member disposed under the throat of the hopper.

6. In a can filling machine, the combination with traveling measuring receptacles of a plate carrying a hopper and having a pivot, adjacent one edge, connecting it with the frame, a yielding compression member disposed under the throat of the hopper, and means for swinging the plate to and fro, with the discharge opening of the hopper over the measuring receptacles, with said pivot as an axis.

In testimony whereof I have signed my name to this specification in the presence of two subscribing witnesses.

CHARLES H. AYARS.
